UNITED STATES PATENT OFFICE

JAMES C. LEDBETTER, OF BROOKLYN, NEW YORK, ASSIGNOR, BY MESNE ASSIGNMENTS, TO THE PROSPERITY COMPANY, INC., OF SYRACUSE, NEW YORK, A CORPORATION OF NEW YORK

GARMENT PRESS

Application filed June 11, 1924, Serial No. 719,260. Renewed May 23, 1929.

This invention relates to garment pressing machines; and a main object of the invention is to produce an improved simplified structure requiring less space and fewer parts in its operating mechanism.

An important purpose of the invention is to produce a pressing machine having correspondingly equal size pressing jaw members possessing a novel movement to provide 10 extended visibility of the work and easy access thereto without at the same time raising the press head high off the buck, a further object being to accomplish this motion with manual operating means, all parts of which 15 are located within the frame of the press to avoid the ordinary present day rearwardly extending horizontal and weighted press lever which usually requires considerable floor space to permit the old style lever to 20 swing up and down to the rear of the press frame. To this end one of my improvements relates to a vertically disposed press lever, the movement of which does not extend beyond the boundary of the pressing machine 25 frame, and my machine therefore requires no more space than the frame itself requires.

Another object of the invention is to produce improved pedal and toggle mechanism, one link of which forms a foot pedal, and 30 this improvement in press closing and locking toggles enables me to eliminate a certain number of parts heretofore necessary in completing toggle mechanism.

The accompanying drawings illustrate a 35 preferred embodiment of the invention and it is understood how changes in construction and mode of operation may be made without departing from the scope and principle of the invention.

The drawing shows a side view of the 40 pressing machine with the press head open. The dotted outline indicates closed position.

Referring further to the drawings for a 45 detailed description of the invention, there is shown a pressing machine frame 5 having a pedestal base 6, an upper buck support 7 together with rearwardly projecting bracket 8; and a table 9 is anchored on ears 10 projecting from the two spaced frame members.

A back table plate 11 may be used to hold the work on the table.

The frame supports a press buck 13, and both pressing jaws, the buck 13 and head 15, 55 may be heated by any suitable means such as steam or electricity, but this is not illustrated because my invention particularly relates to improved construction in the press closing mechanism or operating means to actuate the movable press jaw.

The pressing head 15 is carried on the 60 upper end of a long vertically disposed press lever composed of an upper horizontal arm 16 and a lower lever arm 17 integral therewith. The lever is pivoted at 18 on the frame 65 brackets 8, and reaches over and through the plate 11 to carry the press head 15 back and forth up and down on the buck; and the novel mode of action possessed by the press 70 lever causes the head 15 to undergo a compound rearwardly and upwardly sweeping motion whereby the press head 15 sweeps backwardly from the front edge of the buck 13 as well as rising thereabove, thereby exposing the pressing surface of the buck to 75 extended visibility to provide an unobstructed view of and access to the work. Furthermore in my pressing machine it is not necessary to lift the head 15 so high as with the 80 usual style of pressing machines for the reason that the said head is moved rearwardly, while in present day pressing machines the head must necessarily undergo a rather long movement to gain visibility and access to the work which leads into complicated operating mechanism for performing such high 85 head lift. Instead of operating my press jaws by simple angular jaw spreading movement as in garment presses now used, which after all still leaves the large size press head 90 poised directly over the buck, I combine rectilinear motion therewith which imparts to the head a rearward throwback action simultaneously with the angular rising movement; and to accomplish the results named it is 95 noted that the lever fulcrum point 18 is placed below the meeting or pressing jaw plane and to the rear of the longitudinal axis of the pressing jaws. With the foregoing structure and mode of operation, I may 100

eliminate the usual rearwardly projecting lever arm with the usual exposed counterbalance weight and install it inside the press frame together with a new toggle pedal locking means, the separate elements of which do not wholly constitute my invention, for that more particularly is in the combination.

The lower part of the lever arm 17 projects downwardly in vertical direction and parallel to the frame as shown in the two positions in Figure 1. An improved feature of my invention is the compact design of the operating mechanism whereby the press lever 17 is caused to swing the head entirely away from the buck yet at the same time it remains within the bounds of the frame and does not occupy as much space as present day machines. My machine is intended to be operated by hand or by foot pedal for closing the head thereof, and immediately after the pressing members have made contact, the toggle is further depressed by the operator for the purpose of applying pressure to the work. Preferably the head of the press is closed by hand, and for this purpose a handle 19 is provided on the head by which the operator pulls the head forwardly and downwardly, but it will be shown how a foot pedal may be used in this connection as well.

30 A counterbalance weight acts against the press lever to equalize the weight of the head 15, and to this end a lever 21 is pivoted at 22 on the frame and on one end thereof a weight 23 is fixed while the other end is pivotally connected by a link 24 to a pedal toggle link 26. The weight and leverage of the counterbalance member 23 acts to poise the head 15 in such a manner that an operator may readily pull the head downwardly and forwardly 40 by hand in contact with the buck 13, but the weight 23 preferably overbalances the head to automatically open the press at the end of the pressing period.

A toggle locking and pedal closing mechanism consists of the link 24 pivotally connected to the press lever at 27 and pivotally connected at 29 to a companion link 28; and the lower end of the link 28 is pivoted at 30 on the press frame pedestal base 6. The toggle 26-28 has its rear end pivotally attached to the press lever and its front end pivotally anchored to the frame, and in straightening out, the toggle rapidly swings the head 15 forwardly into pressing position down on the buck; and the toggle reaches an overstraightened position to lock the head closed.

45 A kick-off pedal 32 may be pivoted on the same frame pin 30 for convenience in construction and its rear end 33 reaches underneath the toggle 26-28 and rests in position ready to break the toggle upwardly thereby permitting the press to open under the influence of the counter weight 23.

In the operation of the machine, the operator spreads the work upon the buck 13 and

draws the head closed by using the handle 19 or by depressing the foot pedal 30, or by using both such means if desired. By the time the head 15 reaches engagement with the work, the toggle 26-28 has reached straight line 70 position and has slightly overstraightened itself to produce a locked condition such that the head stands at rest against the work on the buck, and the operator then causes the head to throw up and back off the work by 75 depressing the kick-off pedal.

80 While there is shown a handle 19 and pedal mechanism 26-28 as one form of operating means to open and close the press, it is to be understood that any suitable form of operating means may be used. What is of particular note is the provision of a wide base 6 with a narrow vertical pedestal 5-7 rising thereabove and the V-shaped or triangular bracket 8 extending rearwardly from the frame 85 and the rear fulcrum point 18 being the apex of the bracket and carrying the vertical press lever and the forward fulcrum point 22 carrying the horizontal weight lever. This arrangement of parts is an advantage in the 90 compactness of the machine and reduces the number of parts.

95 What I claim is:

1. A pressing machine comprising in combination, a frame, a press buck carried on the frame, a movable press head coacting with the buck, a press lever pivoted on the frame and disposed in a vertical position and being attached to said head, the press lever frame fulcrum point being located below the pressing plane and to the rear of the longitudinal axis of the head and buck to introduce a compound motion of the head to throw it back away from and above the buck to expose the buck to view, two connected links forming a toggle, a foot piece on one end of one link forming a pedal of the link, one toggle end being pivotally attached to the press lever, the other toggle end being pivotally attached to the frame, kick-off means to break the toggle after it has reached overstraightened position, a weight lever pivoted in the frame, a counter weight on one end of the weight lever to balance the movable press head, and a link connecting the toggle with the weight lever causing the weight to pull upwardly on the toggle.

100 2. A pressing machine comprising in combination, a vertical pedestal frame, a table carried by the frame, a rearwardly projecting bracket carried by the frame and reaching past the table therebelow, a buck mounted on the frame above the table, a movable press head adapted to cooperate with the buck, a press lever standing vertically behind the frame and pivotally carried on the outer end of the bracket to the rear of the frame with its upper end fixed to the press head and its lower end projecting down below the bracket, a horizontal pedal toggle link having its rear 105 110 115 120 125 130

end connected with the lower end of the vertical press lever and a foot piece carried on the front end of the link, and another toggle link one end of which is pivotally connected with the pedal link and the other end connected with the frame.

3. A pressing machine comprising in combination, a vertical pedestal frame, a rearwardly projecting bracket carried by the

10 frame, a table secured to the pedestal frame above the bracket, a buck mounted on the frame above the table, a movable press head adapted to cooperate with the buck, a press lever standing vertically behind the frame

15 and pivotally mounted on the outer end of the bracket with its upper end fixed to the press head and its lower end projecting down below the bracket, a pedal adapted to undergo compound motion simultaneously moving up

20 and down and forward and rearwardly, the rear end of said pedal being attached to the lower end of the press lever, a foot piece carried on the front end of the pedal, and a toggle link having one end pivoted on the

25 frame and the other end pivotally connected with the pedal to the rear of the foot piece.

4. A press comprising, a vertical pedestal frame, cooperating press jaws, a press lever disposed parallel and to the rear of the frame

30 and adapted to open the press, a toggle including a pedal link free of the frame with one end connected to the lower end of the press lever and a link pivoted on the frame, a horizontally disposed weight carrying lever pivoted in the frame at a point toward the front of the frame, a weight mounted on the rear end of the weight carrying lever, and a link connecting the front end of the weight carrying lever to the toggle.

40 5. A press comprising, a vertical pedestal frame, cooperating press jaws, a press lever which includes a substantially vertical portion disposed parallel and to the rear of the frame and attached to one jaw and adapted to open the press, a bracket carried with the frame projecting rearwardly therefrom and pivotally supporting the vertical portion of the press lever, and a toggle including a pedal link free of the frame with one end thereof

50 connected to the lower end of the press lever and another link connected with the pedal and pivoted on the frame, a counterbalance lever pivoted on the frame forward of the bracket, a weight on the rear end of the counterbalance lever and movable up and down proximate the vertical press lever, and means connecting the counterbalance lever with the vertical lever.

6. A press comprising a base with a vertical pedestal frame rising thereabove, a V-shaped bracket carried with the frame above the base and having its apex located at the rear and remotely from the frame, a press buck mounted on the upper end of the vertical frame, a movable press head; a press lever

including a substantially long vertical portion, and a substantially short horizontal portion, the vertical portion being pivoted on the apex aforesaid, and the horizontal portion being anchored to the press head; a horizontally mounted counterbalance lever pivoted on the frame at a point forward of the apex of the bracket, a weight carried by the counterbalance lever, operating means connected with the press lever to actuate the press head, and means connecting the horizontal counterbalance lever with the vertical press lever.

7. In a press, a frame and cooperating jaws thereon, a work table under the jaws and including an upturned back plate extending upwardly behind the jaws, a pivot carried on the frame below the table and disposed to the rear of the plane of the back plate, a jaw-swinging upright including a vertically disposed portion which is mounted on the pivot with substantially two-thirds of its vertical length above the pivot, a horizontally disposed and forwardly reaching arm formed on the upper end of the upright and projecting over and attached to one of the jaws, and operating means disposed in the frame and connected with the lower one-third of the upright which projects straight downwardly under the pivot.

8. In a press, a frame and cooperating jaws thereon, a work table under the jaws and including an upturned back plate extending upwardly behind the jaws, a pivot carried on the frame below the table and disposed to the rear of the plane of the back plate, a jaw-swinging upright including a vertically disposed portion which is mounted on the pivot with substantially two-thirds of its vertical length above the pivot, a horizontally disposed arm formed integrally on the upper end of the upright and projecting forwardly across and attached to one of the jaws and projecting beyond the front edge of said jaw, a handle mounted on the forward end of the horizontal arm to aid in drawing the jaw forwardly, and a pedal means connected to the lower end of the upright and movably rearwardly as the head swings forwardly.

In testimony whereof I affix my signature.
